UNITED STATES PATENT OFFICE.

RICHARD DUANE GREEN, OF TRENTON, NEW JERSEY, ASSIGNOR TO JOHN A. ROEBLING'S SONS COMPANY, OF TRENTON, NEW JERSEY, A CORPORATION OF NEW JERSEY.

WIRE ROPE.

1,405,838.

Specification of Letters Patent. Patented Feb. 7, 1922.

Application filed January 8, 1920, Serial No. 350,152. Renewed August 11, 1921. Serial No. 491,573.

To all whom it may concern:

Be it known that I, RICHARD DUANE GREEN, a citizen of the United States, residing at Trenton, county of Mercer, and 5 State of New Jersey, have invented certain new and useful Improvements in Wire Ropes, fully described and represented in the following specification and the accompanying drawings, forming a part of the 10 same.

Wire ropes for general hoisting purposes, where sheave work requires considerable flexibility, are generally formed with a fibre core of manila or other suitable fibre and the 15 wire strands are laid up helically on this core.

With particularly heavy duties such as encountered in present day commercial use, the excessive tension, by a concentration of 20 pressure on the fibre strands, or the like, eventually causes disintegration of the fibre core. When the fibre core thus ceases to function, the wire strands are supported only by each other, and the result is a 25 tendency of the strand wires to nick. This nicking not only shortens the life of the rope, but tends to lock the strands, thus restricting strand and wire movement when the rope is used in sheaves, causing the wires 30 to break.

It is the especial object of the present invention to provide a heavy duty wire rope such that the fibre core is given a higher compressive resistance and nicking of the 35 strand wires is prevented, and an extended bearing for the rope strands is provided, thus making possible a wire rope of higher efficiency and longer life. The invention is applicable generally to wire rope, however, 40 whether desired for light or heavy duty.

With this general object in view, the invention consists in the combinations, details of construction and arrangement of parts which will first be described in connection 45 with the accompanying drawing and then more particularly pointed out in the claims.

In the drawing:—

Figure 1 is a plan view, with parts broken away, of a wire rope embodying the invention.

Figure 2 is a cross-sectional view taken through the completed rope; and

Figure 3 is a similar view taken through the rope before closing.

Referring to the drawing, there is provided a plurality of wire strands 11 helically laid up on a multiple core hereinafter described. Each strand 11 preferably consists of a plurality of individual small wires which are preferably of high carbon steel 60 and are helically laid up on each other in the usual manner of making wire rope strands. Although six wire strands of nineteen wires each are shown, it is understood that any other suitable arrangement may be 65 used.

The invention includes a multiple core having a plurality of compressible strands, of which one serves as a center core and about which the others are helically laid up 70 to provide separating bearers for the wire strands. In the embodiment here shown, there is provided a multiple core including a center core 12. This is shown as a fibre core formed of a number of fibre strands of 75 manila or the like helically laid up in the usual manner of a fibre core. In structures embodying the invention to the best advantage there is provided a tenacious protector for the center core. The exemplification of the tenacious protector here shown is a narrow, flat, steel band or flat wire 13, helically laid up on the fibre core. The band or flat wire 13 is preferably laid up under considerable tension, so that the core 80 is placed under an initial compression. Also the band or flat wire is preferably so wound that the edges of adjacent convolutions are substantially contiguous so as to fully enclose the core and hold the lubrication therein. These edges are shown as square but they may be rounded if desired, and this may be preferable, especially in large ropes as avoiding all possibility of the edges cutting the core. A half round or similar form of band 95 may be used, with the rounded side next the core, which will taper off the pressure on the core and reduce liability to injuring the core in bending over sheaves. For convenience in manufacture, the protecting band 13 may 100 be of several alternating pieces, two being shown in the drawing.

In the present embodiment the bearer members 14 of the multiple core are like the

center core 12 except that they are shown as somewhat smaller in size. These bearing members 14 are served with tenacious protectors 15 which are here shown as like the 5 tenacious protectors 13 of the center core except that the protectors 15 are preferably of soft, annealed steel, so as to be deformable, whereas the protector 13 for the center core is preferably, though not necessarily, 10 hard and substantially non-deformable.

The bearer members 14 of the multiple core are laid up on the center core with the same pitch as the wire strands 11 and so as to lie between them.

15 The construction described provides a multiple core comprising a center core and a number of separating bearers deformable under the tension of the wire strands to substantially conform to the configuration 20 thereof. Figure 3 illustrates the relation of the parts before the rope is closed. Upon closing, the tension exerted by the wire strands deforms the bearer members 14 of the multiple core so that they substantially 25 conform to the configuration of the wire strands. This deformation is increased when the completed rope is placed under high tension work. Under this deformation the core members 14 take some such 30 form as that shown in Figs. 1 and 2, thus providing an extended bearing layer for the wire strands which separates the strands from one another and from the center core.

With the construction described concentrated 35 pressure on the fibre strands of the center core is prevented. The initial pressure given the fibre core 12 in laying up the protecting band 13, when such is used, flattens out, to a certain extent, the corrugations 40 of the fibre strands, thus presenting a more cylindrical surface to the protector. The center core has a much higher degree of compressive resistance than in the case of the usual fibre core ropes, and the life of the rope 45 is prolonged. The separating bearers provided by the outer members 14 of the multiple core prevent nicking of the strand wires and the extent of "flow" of these core members into the configuration of the wire 50 strands, under the tension thereof, provides an effective and uniform separation of the wire strands that gives a better spacing of the latter. The strands and wire move more freely, better lubrication is made possible 55 and the rope is more flexible and has a higher degree of efficiency, that is, a higher percentage of the total strength of the component wires, than the usual fibre center ropes.

While the invention has been described in 60 connection with fibre or rope strand cores, and is especially valuable in such use, it will be understood that the invention, considered broadly, is applicable with other compressible cores as defined by the claims; and that 65 while the separating bearers have been de-

scribed as being fibre or similar strands, they may be formed of other material, such that they are deformable under the tension of the wire strands to substantially conform to the configuration thereof.

70

What I claim is:

1. A wire rope comprising a multiple core having a plurality of compressible strands, one of which serves as a center core and about which the others are helically laid up, tenacious protectors for said strands, and a plurality of wire strands helically laid up on said multiple core.

75

2. A wire rope comprising a multiple core having a plurality of compressible strands, one of which serves as a center core and about which the others are helically laid up, a hard, tenacious protector for the center core, deformable, tenacious protectors for the other strands, and a plurality of wire strands helically laid up on said multiple core.

80

3. A wire rope comprising a multiple core having a plurality of compressible strands, one of which serves as a center core and about which the others are helically laid up to serve as separating bearers, tenacious protectors for said bearer strands, and a plurality of wire strands helically laid up on said multiple core.

85

4. A wire rope comprising a multiple core having a plurality of compressible strands, one of which serves as a center core, and about which the others are helically laid up to serve as separating bearers, tenacious protectors for said bearer strands, and a tenacious protector for said center core helically laid up on said core to place the same under an initial compression, and a plurality of wire strands helically laid up on said multiple core.

90

5. A wire rope comprising a plurality of helically laid up wire strands, and a multiple core for said wire strands having a compressible center core, a plurality of compressible strands deformable under the tension of the wire strands to substantially conform to the configuration thereof, and tenacious protectors for the members of said multiple core.

100

6. A wire rope comprising a plurality of helically laid up wire strands, a multiple core for said wire strands having a compressible center core, a plurality of compressible strands deformable under the tension of the wire strands to substantially conform to the configuration thereof, and deformable tenacious protectors for said deformable strands.

105

7. A wire rope comprising a multiple fibre core having a plurality of fibre strands, one of which serves as a center core and about which the others are helically laid up, tenacious protectors for said fibre strands, and a plurality of wire strands helically laid up about said multiple core.

110

8. A wire rope comprising a multiple fibre core having a plurality of fibre strands, one

115

of which serves as a center core and about which the others are helically laid up to serve as separating bearers, tenacious protectors for said bearer strands, and a plurality of 5 wire strands helically laid up about said multiple core.

9. A wire rope comprising a multiple core having a plurality of compressible strands, one of which serves as a center core, and 10 about which the others are helically laid up

to serve as separating bearers, tenacious protectors for the strands of said multiple core laid up on said strands to place the same under an initial compression, and a plurality of wire strands helically laid up about said 15 multiple core.

In testimony whereof, I have hereunto set my hand.

RICHARD DUANE GREEN.
